[57] CLAIM

The ornamental design for a smoke detector, as shown
and described.

DESCRIPTION

FIG. 1 is a perspective view of a smoke detector showing
our new design;
FIG. 2 is a top plan view thereof;
FIG. 3 is a bottom plan view thereof;
FIG. 4 is a front elevational view thereof with the oppo-
site side a mirror image of FIG. 4; and
FIG. 5 is a left end elevational view thereof with the
opposite end a mirror image of FIG. 5.
